UNITED STATES PATENT OFFICE.

CONRAD T. HANSEN, OF PHILADELPHIA, PENNSYLVANIA, ASSIGNOR TO AMERICAN MOTOR BODY COMPANY, OF PHILADELPHIA, PENNSYLVANIA, A CORPORATION OF DELAWARE.

CAR SEAT.

Application filed March 10, 1922. Serial No. 542,555.

To all whom it may concern:

Be it known that I, CONRAD T. HANSEN, a citizen of the United States, residing at Germantown, in the city of Philadelphia, 5 county of Philadelphia, and State of Pennsylvania, have invented certain new and useful Improvements in Car Seats, of which the following is a specification.

My invention relates to car seats and more particularly to a car seat designed so as to be made almost entirely of metal and of the type commonly referred to as "reversible." One of the aims of my invention is to provide a seat which is light in weight, inexpensive to construct, which provides an increased length of cushion and is efficient in operation. A further object is to provide a reversible car seat which permits of its being shipped in dismantled condition so that 20 certain of the parts such as the wall plates, may be installed in the car by the builder during the construction of the car and before the installation of the complete seat. Another object of my invention is to provide a reversible seat which permits of the use of a thin, narrow and light rocker and whereby accommodation of different types 25 of cushions may be readily and easily secured by changing the height of the rocker supporting members rather than by increasing the size of the rocker or by lowering the rocker to a point where it extends below the bottom of the end plates and rails, as has 30 usually been the case heretofore. A further object of my invention is to so construct the 35 seat that no part of the mechanism extends below the rails or end plates and a clear space is provided under the seat for electric heating devices or for luggage, etc. An- 40 other object of my invention is to provide a seat wherein the throw-lever is adapted to give a large amount of throw to the cushion and thereby to overcome the objectionable feature of having the cushion project in the 45 rear beyond the back, and also having the advantage of giving a wider seating space on the cushion. A further object of my invention is to provide a seat-throwing mechanism wherein the throw-lever, when in- 50 final position, lies at a sharp angle to the standard, thus giving a better bearing against the standard and holding the back more firmly in place, and giving the back greater stability than has been obtained by

constructions heretofore known. A further object of my invention is to provide a seat having an easy operable automatic foot rest, the construction being such that there is a minimum of lost motion in the operating parts of the foot rest and a very firm and rigid foot rail is provided. Other objects will be in part obvious and in part pointed out hereinafter.

In order that a clearer understanding of my invention may be had attention is hereby directed to the accompanying drawings forming a part of this application and illustrating certain possible embodiments of my invention. In the drawings Fig. 1 is a side elevation of a car seat embodying my invention, portions of the construction being shown in section; Fig. 2 is a view similar to the view shown in Fig. 1 but with the parts in a different position; Fig. 3 is a vertical section taken on the line 3—3 of Fig. 2; Fig. 4 is a sectional view taken on the line 4—4 of Fig. 2; Fig. 5 is a sectional view of a detail of the construction and is taken on the line 5—5 of Fig. 2; Fig. 6 is an end elevation of a part of a car seat embodying my invention showing a modified form of seat reversing mechanism; Fig. 7 is a detail view showing the rocker supporting means, the rocker support being shown in section; Fig. 8 shows a portion of the end plate in section and is taken on the line 8—8 of Fig. 2.

Similar reference characters designate similar parts throughout the several views of the drawings.

Referring to the drawings, the seat back 1 is supported upon a pair of oppositely disposed standards 2, each having a pair of rollers 3 at their lower ends. Instead of forming a grooved or channeled track for the rollers in a member separate from the end plate and riveting or welding the track to the end plate, I form a track 4 in the end plate 5 by cutting an opening therein and pressing the edges inwardly to form the flanges of the track as at 4. This leaves an opening through the end plate at the wall end of the seat, but as the plate is secured to the side of the car, this is not objectionable. At the aisle end the usual thin steel cover plate 6 may be used on the outside of the main steel plate 5 to cover the opening. If desired, the flanges 4 which form the track may be reinforced by pieces of angle

shaped steel 7 secured by suitable means, as by welding, over the upper flange 4 just over the place where the outer roller in the standard rests when the seat back is in position for use. A reinforcement 8 may also be welded or otherwise secured at the end of the flanges 4 to take the strain of the downward pressure of the outside roller when the back is in position for use. This construction of track saves several pounds in weight and is cheaper than the separate track construction ordinarily used heretofore.

Heretofore the seat rails were attached to the wall plates by attaching steel angle plates to the ends of the seat rails and bolting the angle plates through the end plates of the seat. In accordance with my invention an angle plate 9 is permanently riveted, as at 10, to the end plate itself and the rail 11 is bolted, as at 12, to the angle plate. The advantages of this method over the other are that the steel angle plate is formed with a flange 13 which fits over the rail 11, giving a firm bearing, and further, it permits of shipping the wall plates, as 5, in advance, where so desired by the car builder, in order that they may be attached to the steel or wood side of the car during the construction of the same. Usually, the seat must be put together, including the bolting on of the wall plate, and then the entire seat secured to the side of the car. By means of my invention, the wall plate may be attached to the wall before the connecting rails are attached and the rails need only be bolted to the angle plates carried on the wall plates.

Ordinarily the rocker is supplied with a flange at the bottom mounted to slide back and forth in a slot cut into the angle plate or the rail. According to my invention the angle plate 9 is made with a projection 14 extending upwardly to any required height, and with a pin 15 projecting from the top of the same. The pin is adapted to extend through a slot or groove 16 formed in the lower part of the rocker 17 and has an enlarged head 42 adapted to abut against the rocker on the opposite side. The advantage of my improved construction is that it makes possible the use of thinner, narrower and lighter rockers, and the variation in the thickness of the cushion, as required by different types of seats, may be regulated, for the most part, by the height of the projecting part 14 of the angle plate 9 rather than by increasing the size of the rocker or by lowering the rocker to a point where it extends below the bottom of the end plates and rails, as is the case in the usual construction of seats of similar character. It is to be observed that by means of my invention there is no part of the mechanism which extends below the rails or end plates even when the back is in the centre and the rocker in its lowest position, and thereby an abundance

of clear space is provided under the seat for the installation of electric heating devices or for the storage of luggage or other articles.

The rocker 17 is preferably of pressed steel and is adapted to support seat cushion 18 upon a horizontally extending flange 19, the cushion being held in place by the usual dowel pins 20. The rocker 17 is adapted to be operated by movement back and forth over the pin 15 projecting through the slot 16. The slot is preferably flanged as at 21, and is so shaped as to lower the rocker as it passes under the back when the latter is in a central position (see Fig. 2) and gives an end bearing on both sides when the rocker is in its final position and the seat ready for occupancy. If desired, the end of the slot 16 may be provided with a slight depression, as at 22 (Fig. 7) in the upper part thereof thus locking the seat to a slight extent when in position for use. The central portion of the rocker slot 16 may be provided with a larger opening, as at 23, which permits the head 42 of the pin 15 to pass therethrough. Thus, the rocker may be removed by moving the back into central position which brings the enlarged portion 23 of the rocker slot 16 opposite the pin 15 and permits the head 42 to pass through the slot in the rocker.

The numeral 24 designates a double throw-lever, which is pivoted as at 25 intermediate its ends to the end plate 5, instead of having its pivotal point on the cross-rod as is usually the case. The upper end of the throw-lever 24 has a pin 27 slidably mounted in the vertical slot 26 in the supporting standard 2, and the opposite end of the lever 24 is widened out as at 28 and carries two pins 29 and 30, respectively, in separated relation. Two flanged slots are provided on the rocker 17 adapted to cooperate with the pins 29 and 30 to effect the movement of the cushion when the seat back is moved. As shown, the flanged members may comprise channel pieces secured to the rocker, one of said pieces 31 being provided for the pin 29 and the other 32 being provided for the pin 30. Pins 29 and 30 and the slots 31 and 32 are so arranged that when the seat back is in position for use (see Fig. 1) one of the pins, such as 30, will be in the slot of the member 32 provided therefor, the pin 29 being separated from its cooperating slot member 31. When the seat back is moved toward the central position, pins 29 and 30 rotate about the pivot point 25 of the lever and the pin 30 will cooperate with the flanged slot member 32 to push the rocker 17 and the seat cushion 18 in the reverse direction, pin 29 meanwhile approaching its slotted member 31. When the seat back is in central position (see Fig. 2) the construction is so designed that both the pins 29 and 30 will be seated in their respective flanged slot members 31 and 32. Then when the seat back is

- moved further toward the other extreme position, the rotation of the pins 29 and 30 about the axis 25 continues, causing the pin 30 to leave its slotted flange member 32 but causes the cooperation between the pin 29 and its slotted flange member 31 to continue the movement of the rocker 17 and the seat cushion 18 in the reverse direction to the movement of the seat back 1.
- 10 It is to be noticed that one of the pins, 29 or 30, is at all times in one of the flanged slot members 31 or 32 of the rocker 17 and a continual positive and firm connection is maintained between the throw-lever 24, the 15 seat standard 2 and the rocker 17. The cushion 18 is moved a considerable distance and a sufficient distance to overcome the objectionable feature of having the cushion project in the rear beyond the seat back, 20 and moreover has the advantage of giving wider seating space on the cushion. It is also to be noticed that by means of my construction the throw-lever 24, when in final position, lies at an angle which is less obtuse than is usual in seats of this character. Thus, my invention secures a better bearing at the upper portion of the lever 24 against the standard 2, the result being, that while the back 1 may be moved with sufficient ease, it is held firmly in place when in 25 position for use and greater stability is given to the back. The flat position of throw-lever 24 also increases the throw of the cushion.
- 30 As a modification of my invention, instead of providing two pins, such as 29 and 30, on the throw-lever 24 and two cooperating flanged slots, as provided by members 31 and 32 on the rocker 17 to cooperate with these pins, I may provide a single pin or other element 33 which is adapted to cooperate with a single flanged slot 34 in the rocker 17 to effect the reverse movement of the seat-cushion whenever the seat back is 35 moved. This modification is illustrated in Fig. 6 wherein the throw-lever 24 is not widened at its lower end but carries an oscillating rod 33 which is continually seated in a vertical slot 34 formed in the rocker 17 and cooperates therewith to effect the desired throw of the cushion. Although this single pin connection does not give quite as much throw to the cushion as the double pin arrangement above described, however, 40 on account of the flat position of the throw-lever 24, a considerable amount of throw is obtained.
- 45 It is to be understood that the mechanism above described may be, and preferably is, duplicated at each of the two ends of the seat. In order to obtain unitary movement between the two ends of the seat, I provide an oscillating rod 33 extending from end to end of the seat, each end being mounted 50 as at 35 to the lower end of the throw-lever 55
24. Formerly, this rod 33 was projected into an opening in the end plates of the seat and was attached thereto. By my construction it is easy to adapt an automatic foot rest for operation by the oscillating rod 33. 70 The foot rest comprises a foot rail 36, extending from side to side under the seat. Each end of the rod 33 is supported by a metal lever arm or hanger 37 which is pivoted as at 38 to a light steel bridge 39 attached at each end and supported by connecting rails 11. The lever 37 has a portion 40 beyond its pivot point 38, which portion is provided with a flanged slot 41 in which the oscillating rod 33 is adapted to 80 move and with which the oscillating rod 33 cooperates to effect the desired movement of the lever 37 and the foot rail 36. This method does away with the usual cog and pinion members required to reverse the motion of the foot-rest and ordinarily found in seats of this character. It is also to be noticed that the operating parts of the foot rest and the foot rail itself is very firm and rigid since the foot-rest hanger or lever 37 85 has its bearing at the top against the oscillating rod 33 which is attached to the ends of the throw-levers 24, these levers 24 being pivoted as at 25 into the end plates 5 of the seat. 90
- 95 This seat may be mounted in a car in any one of a number of well known fashions. For instance, a pedestal may be supplied and may be attached to the rails 11 in the usual manner. Obviously, an arm rest may 100 be attached to the aisle plate by bolts or other well known means, if desired.
- 105 As many changes could be made in the above construction and as many apparently widely different embodiments of this invention could be made without departing from the scope thereof, it is intended that all matter contained in the above description, or shown in the accompanying drawings shall be interpreted as illustrative and not 110 in a limiting sense.
- 110 What I claim is:
1. In a car seat, in combination, an end plate, an angle plate secured to the end plate, a cross rail secured to the angle plate, said angle plate having a flange fitting over the top of said rail constituting a firm superposed bearing therefor. 115
  2. In a car seat, in combination, an end plate, an angle plate attached to said end plate, an upwardly extending projection on said angle plate, a pin extending from said projection, a seat rocker having a slot, said pin and slot cooperating to support said rocker for reciprocating movement on said pin. 120
  3. In a car seat, in combination, shiftable seat rockers having slots, members extending through said slots supporting said rockers, means comprising retainers on said members 125
  - 130

alongside of said rockers and wider than the width of the main portion of the slots for preventing lateral displacement of said rockers, each of said slots at one place being wider than said retainers to permit lateral movement of said rockers on said supporting members.

4. In a car seat, in combination, an end plate, an angle plate attached to said end plate, an upwardly extending projection on said angle plate, a pin extending from said projection, a seat rocker having a slot, said pin and slot cooperating to support said rocker for reciprocating movement on said pin, said pin having a head, and said slot having a centrally located portion wider than the head of the pin to permit the removal of the rocker therefrom.

5. In a car seat, in combination, an end plate, an angle plate attached to said end plate, an upwardly extending projection on said angle plate, a pin extending from said projection, a seat rocker having a slot, said pin and slot cooperating to support said rocker for reciprocating movement on said pin, and a cross rail attached to and supported by said angle plate.

6. In a car seat, in combination, an end plate, an angle plate attached to said end plate, an upwardly extending projection on said angle plate, a pin extending from said projection, a seat rocker having a slot, said pin and slot cooperating to support said rocker for reciprocating movement on said pin, and a cross rail attached to and supported by said angle plate, said angle plate having a flange fitting over the top of said rail providing a bearing therefor from above.

40 7. In a car seat, in combination, a throw-lever pivoted intermediate its ends, a back supporting standard, a rocker, a pair of flanged slot members on said rocker, a pair of pins on said throw-lever adapted during

the reciprocation of the throw lever to enter 45 and to leave said slot members at the tops and to cooperate with said flanged slotted members whereby movement of said throw-lever about its pivot effects the throw of said rocker, and a pin and slot connection between 50 the upper end of said throw-lever and said standard whereby movement of said seat back causes movement of said throw-lever, and permits reciprocation of said standard in a substantially horizontal plane. 55

8. In a car seat, in combination, an end plate having an opening bounded by pressed-in edges providing a channel track for back supporting rollers, an angle plate riveted to said end plate, a cross rail bolted to said angle plate, a flange formed integrally on said angle plate and fitting over said rail providing a firm bearing therefor, an upwardly extending projection integrally formed on said angle plate, a pin extending from the upper portion of said projection, a seat rocker having a slot, said pin and slot cooperating to support said rocker for reciprocating movement on said pin, said pin having a head, said slot having a centrally 65 located portion wider than the head of the pin to permit the removal of the rocker therefrom, a throw-lever pivotally mounted intermediate its ends on said end plate, a back supporting standard, means connecting 70 said throw-lever to said standard and to said rocker, whereby movement of said standard affects movement of said seat rocker, an oscillating rod carried on said throw-lever below its point of pivotal support and 75 movable therewith, and a connection between said oscillating rod and seat mechanism at each end of the seat, whereby corresponding 80 parts of the seat mechanism at each end of the seat are caused to move in unison. 85

This specification signed this 6th day of March, 1922.

CONRAD T. HANSEN.
